UNITED STATES PATENT OFFICE.

NICHOLAS S. VEDDER, OF TROY, AND TOBIAS S. HEISTER, OF LANSINGBURG,
N. Y., ASSIGNORS TO JOSEPH BELL & CO., OF WHEELING, WEST VA.

DESIGN FOR HEATING-STOVES.

Specification forming part of Design No. 7,965, dated December 29, 1874; application filed December 14, 1874.
[Term of Patent 7 years.]

To all whom it may concern:

Be it known that we, NICHOLAS S. VEDDER, of the city of Troy, in the county of Rensselaer, and State of New York, and TOBIAS S. HEISTER, of Lansingburg, in said county and State, have jointly invented and produced a new and original Design for Heating-Stoves, of which the following is a specification, reference being had to the accompanying photograph of a stove having our said new design.

One part of this invention consists of the design for the top plate A of the base-section, as composed of its general square form, with rounded corners, and the lower surrounding and projecting convex border-molding b, the flat ornamented top corners c, and the intermediate inclined and concave parts d, having the ornaments e thereon, all shaped and arranged together so as to appear substantially as represented in the aforesaid photograph.

Another part consists of the design for the panel-border of the plate I, as composed of the compound corner ornaments j and ornamented side moldings k, all shaped and arranged as shown in the accompanying photograph.

Another part consists of the design for the side plate or panel I, composed of the central ornament F and the border j k, all shaped and arranged with the intervening plain surface l, so as to appear as shown in the aforesaid photographic representation.

Another part consists of the design for the upright corner-pieces M of the base-section, as composed of the bent or curved base-molding n at the bottom, and the series of separate oblong bent projections o, arranged horizontally on the curved surface p, and each surrounded by the base-fillet q, and having the upper and lower sides beveled to an edge, and the ends inclined, and the whole formed and disposed as represented in the aforesaid photograph.

Another part consists of the design for the base-plate R, composed of the rounded corners s, inner angles t, concave inner molding u, plain flat surface r, widest in front, and the border formed of the upper concave molding w, the lower convex molding x, and the intermediate ornamentations y, all shaped and combined as shown in the photograph aforesaid.

What we claim as our joint invention is—

1. The design for the top plate A of the base-section, as composed of its general square form, with rounded corners, convex molding b, flat ornamented top surfaces c, and inclined and curved portion d, with the ornaments e thereon, all shaped and arranged as shown and described.

2. The design for the panel-border of the plate I, consisting of the compound corner ornaments j and ornamental side moldings k, all shaped and arranged together as described and shown.

3. The design for the plate or panel I, composed of the central compound ornament F, border j k, and plain surface l, all shaped and disposed together as described.

4. The design for the corner-pieces M, consisting of the curved bottom molding n, curved surface p, and series of oblong angular projections o, each surrounded by the base-fillet q, as specified and shown.

5. The design for the base-plate R, as composed of the rounded corners s, inner angles t, concave molding u, flat surface r, concave molding w, convex molding x, and the series of ornaments y, all shaped and disposed as shown.

In testimony whereof we hereunto subscribe our names this 1st day of December, 1874.

NICHOLAS S. VEDDER,
TOBIAS S. HEISTER.
